Primary Examiner — Clare E Heflin(74) *Attorney, Agent, or Firm* — McCarter & English, LLP(57) **CLAIM**

The ornamental design for a lamp, as shown and described.

DESCRIPTION

FIG. 1 is a front perspective view of a first embodiment of a lamp in the form of a hanging lamp;

FIG. 2 shows a bottom perspective view of FIG. 1;

FIG. 3 shows a front elevational view of FIG. 1;

FIG. 4 shows a right side view of FIG. 1, the left side being a mirror image thereof;

FIG. 5 is a front perspective view of a second embodiment of a lamp in the form of a hanging lamp;

FIG. 6 shows a bottom perspective view of FIG. 5;

FIG. 7 shows a front elevational view of FIG. 5;

FIG. 8 shows a right side view of FIG. 5, the left side being a mirror image thereof;

FIG. 9 is a side perspective view of a third embodiment of a lamp in the form of a hanging lamp;

FIG. 10 shows a bottom perspective view of FIG. 9;

FIG. 11 shows a front elevational view of FIG. 9; and,

FIG. 12 shows a right side view of FIG. 9, the left side being a mirror image thereof.

The broken lines shown on the drawings depict portions of the lamp that form no part of the claimed design.
